FISHING THERMOMETER INSTRUMENT

Horst M. Krenz, St. Joseph, Mich., assignor to Heath
Company, Benton Harbor, Mich.

Filed Oct. 8, 1971, Ser. No. 187,707

Term of patent 14 years

Int. Cl. D22—05

U.S. Cl. D22—99

FIG. 1

FIG. 2

FIG. 3

FIG. 4

FIG.5

FIG.6

FIG. 1 is a front elevation view of a fishing thermometer instrument embodying my new design;
FIG. 2 is a rear elevation view thereof;
FIG. 3 is a top view thereof;
FIG. 4 is a bottom view thereof;
FIG. 5 is a right side elevation view thereof; and
FIG. 6 is a left side elevation view of the instrument.
I claim:

The ornamental design for a fishing thermometer instrument, substantially as shown.
